A. H. HALL AND H. T. LEE, OF MARYSVILLE, CALIFORNIA.

Letters Patent No. 91,120, dated June 8, 1869.

IMPROVEMENT IN STEAM-PACKING.

The Schedule referred to in these Letters Patent and making part of the same.

To all whom it may concern:

Be it known that we, A. H. HALL, and H. T. LEE, of Marysville, in the county of Yuba, and State of California, have invented a new and useful Method of Packing Steam-Joints; and we do hereby declare that the following is a full and exact description of the same, reference being had to the accompanying drawings, and to the letters of reference marked thereon.

In the drawings—

Figure 1 represents a perspective view of a steam-chest packed.

Figure 2 is a transverse section, showing the packing enclosed in the joint.

Figure 3 is a section of a strip of the packing, already upset and ready for use.

The nature of our invention consists in peculiarly constructing strips of malleable metal, as copper, brass, &c., which are placed in the joints of steam-chests, and also in the joints of steam and water-pipes, in the same manner as other packing is used, and then upsetting them on each edge.

A represents a steam-chest, provided with the top *a*, which is suitably attached thereto.

In the joint, between the top *a* and the chest A, is

placed the metal strip *a'*, which may be of any suitable material.

The edges of the latter project at each side of the joint, and are upset on each side, thus forming a secure joint.

The advantage of this mode of packing consists in sinking the inside as well as the outside edge of the joint into the upset part of the packing, thereby making the inside, as well as the outside edge, steam-tight.

The joints may be taken apart as often as required, without injuring the packing, thereby affecting a great saving.

We do not claim the kinds of metal used, but

What we claim, and desire to secure by Letters Patent, is—

The construction of the malleable metal strips, substantially as described, and for the purpose set forth.

This specification signed and witnessed, this 9th day of February, 1869.

A. H. HALL.
H. T. LEE.
